COWLING COMBINATION

Karl Adolph, Esslingen-on-the-Neckar, Germany,
assignor to the firm J. Eberspacher, Esslingen-
on-the-Neckar, Germany, a corporation of Ger-
many

Application January 16, 1939, Serial No. 251,164
In Germany February 12, 1938

2 Claims. (Cl. 123—171)

This invention relates to air flow governing means for internal combustion engines, more especially for air-cooled motors of airplanes.

It is well-known to arrange for this purpose 5 a cowl surrounding the whole motor in the form of a ring and having a stream-line-profile. The cooling air entering at the front side of this cowling ring passes the cylinders of the engine and then escapes through a split provided between 10 the cowling ring and the body of the airplane behind the motor.

Now I have found that this kind of cowling ring is insufficient to fulfill the enhanced requirements in cooling, especially at low flying speeds, 15 the gradient of pressure between the entrance and discharge being petty and therefore the quantity of cooling air passing through the cowling ring being too small.

At the outer side of such cowling rings, near 20 the fore-edge, there arises a field of strongly reduced pressure. Therefore one has decided to arrange the air-split no more at the rear end of the cowling ring but to bend the cowling ring on its front side in an arcuate way inwards and 25 to leave in the cowling ring an annular split discharging into the field of reduced pressure. Thus the cooling-air enters the cowling ring at its front-side and also escapes at the front side through the annular split. Hereby a considerably 30 higher difference of pressure between entrance and discharge of the air is available. Nevertheless also with such a cowling ring the efficiency is increased only to a moderate extent, because the field of reduced pressure is not always pro- 35 duced at the same point on the outside of the cowling ring but its position and amount depends upon the conditions of flight prevailing every moment, i. e. it varies with the direction and the speed of the flight and with the number of revolutions of the propeller.

The invention relates to air flow governing means for internal combustion engines, especially motors of airplanes, comprising an outer stream-line cowl annularly and concentrically encom- 45 passing the engine from the outside, and a similar inner cowling ring forming together with the outer cowling ring an annular channel and being separated from the outer cowling ring at its front side by one or more splits, the said splits 50 being surrounded at a certain distance by a further cowling ring the radial cross-section of which is also streamlined.

The invention is illustrated by way of example in the annexed drawing which is a diagrammatic axial cross-section. The outlines of the

motor are shown in elevation by dotted lines. The motor is surrounded by an outer cowling ring *a* which is closed at its rear side by a partition *l*. This outer cowling ring *a* is continued inwardly by a second cowling ring *b* bent at its 5 fore-part toward the fore-edge of the outer cowling ring *a* to form the partition *c* and having apertures on its periphery to receive the extended portions of the radially disposed cylinder heads of the engine. Between the fore-edge of the outer cowling ring *a* and the curved part *c* of the inner cowling ring *b* an annular split *d* is left. A further annular cowling ring *e* is arranged to surround in a certain distance the annular split *d*. The part *e* may be shaped in the form of 10 a hollow body or a sheet.

The cooling air entering the inner cowling ring *b* in the direction of the arrows *f* first passes the motor cylinders and other hot parts to be cooled, then is turned over by a partition *l* and flows 20 through the annular channel *m* left free between the cowling rings *a* and *b* in the direction of the arrow *g* forward and toward the discharge split *d*. This split leads into the annular channel *n* which is left free between the annular mem- 25 ber *e* and the cowling rings *a* and *b* and which is passed, in the direction of the arrow *h*, by the air flowing in from the outside.

At the opening of the discharge split *d* always 30 a negative pressure is prevailing owing to the streaming *h* which pressure retains its place independent of the conditions of the flight. Consequently the cooling air moving in the direction of the arrow *g* and passing the cylinder heads 35 of the motor is sucked off at the discharge split *d* and carried away by the streaming *h* at the outside of the outer cowling ring *a*.

In this way I attain that the split *d* leading off the cooling air does not lie in the direct air current which depending upon the direction 40 of the arriving flow, the number of revolutions of the propeller and the speed of flying produces a field of reduced air pressure at different points. On the contrary, the discharge split *d* is exempt 45 from these various influences inasmuch as a dislocation of the reduced pressure practically takes place only outside the member *e*, whereas the nozzle-shaped channel *n* between this member *e* and the cowling rings *a* and *b* is not affected by the dislocation of the field of reduced pressure. 50

The conditions of streaming may be varied by displacing the member *e* in the direction of the arrows *i*—*k*, in other words axially whereby the nozzle-shaped cross-section of the annular channel *n* between the member *e* and the members *a* 55

and c is modified, and any desired control of the cooling action may be obtained. Owing to the strongly reduced pressure acting on the outer face of the member e , only weak governing forces 5 are required for this control.

For instance, if the control is to be automatically and changeably adjusted to constant spark-plug temperature of the airplane motor or to another essential structural element, the control 10 may be effected by a thermostatic device.

I claim:

1. A cowling combination for an air cooled combustion engine, comprising an outer streamlined cowling ring concentrically encompassing 15 the engine at a predetermined distance and being closed at its rear side behind the engine, a second streamlined cowling ring arranged within in said outer cowling ring and leaving an annu-

lar channel between said rings, the inner cowling ring having apertures on its periphery to receive the extended portions of the radially disposed cylinder heads of the engine and being bent at its fore-part in an arcuate way toward the fore-edge of the outer cowling ring, whereby an annular split is left between the bent-over edge of the inner cowling ring and the fore-edge of the outer cowling ring, and a third streamlined ring surrounding at a predetermined 10 distance said first and second rings at the portion thereof forming said annular split.

2. In a cowling combination in accordance with claim 1, means for displacing said third streamlined ring in the direction of the axis of 15 the engine.

KARL ADOLPH.
